METHOD OF MAKING FILAMENTS FOR
MINIATURE INCANDESCENT LAMPS AND
ARTICLES

William J. Henry, Akron, Ohio

Application June 27, 1932, Serial No. 619,421

1 Claim. (Cl. 176—40)

This invention relates to incandescent lamps and procedure and apparatus for making the same.

It has heretofore been desirable to produce a small, round source of illumination for use in optical instruments such as a retinoscope (or skiascope), but so far such light source has not been obtainable. It has also been proposed heretofore to provide incandescent lamps for various uses in which a double helical filament coil is employed. These incandescent lamps, however, have not been satisfactory because of shorting due to touching of adjacent coils of the double helix.

It has been found by the present inventor that a double helical coil may be effectively provided for use in optical instruments to provide a small, perfectly round light source which will be very effective in the determination of defects in the eye by the use of such instruments as the retinoscope if the diameter of the double helical coil as compared with the size of the filament is such that the double helical coil will be stiff enough so that it cannot be distorted or shorted by the ordinary jars or shocks to which these bulbs are subjected in service and if the double helical coil is made by the method disclosed herein to prevent touching of the adjacent convolutions of the coils in service.

The present inventor has discovered that the natural expansion of the filament wire under heat results, in a double helical coil, in the distortion which causes movement of the adjacent coils with respect to each other, which movement has heretofore caused shorting, and that by winding the coils as disclosed herein with an uneven spacing and preheating the coils whereby this distortion is caused to relatively move the coils to more or less equal spacing, the danger of shorting by touching of the coils is eliminated, any movement which occurs in the coils when subsequently used tending, if anything, to move the coils farther apart.

The double helical coil in an optical instrument is especially effective since in a comparatively short filament of small diameter the leads or mounting wires absorb so much of the heat as to prevent the ends of the filament from heating to the extent of the middle. The outer end, therefore, of the double helical coil gives the greatest amount of light, and when an incandescent bulb of this construction is mounted so that the source of light from the lamp in effect is the outer end of the coil, a perfectly round

and true light source of small diameter is provided.

The present invention, accordingly, has for its general purpose the provision of an incandescent lamp having an improved double helical coil construction and the provision of an improved method and improved apparatus for making such an incandescent lamp.

The invention is illustrated in the accompanying drawing and described in somewhat more detail below. It is to be understood that the invention is not limited to the specific form thereof illustrated and described.

Of the accompanying drawing,

Figure 1 is an elevation, partly in section, of 15 a coil winding equipment embodying the invention;

Figure 2 is an enlarged plan view thereof;

Figure 3 is a view similar to Figure 2 showing the coil as wound therein and illustrating 20 the manner of attaching the leads to the coil;

Figure 4 is a right end view of Figure 3;

Figure 5 is an elevation of an incandescent lamp embodying the invention; and

Figure 5a is an enlarged view of the improved 25 filament as shown in Figure 5.

Referring to the drawing, the numeral 10 designates a coil winding mandrel which is secured on a rotatable shaft 11 which may be mounted in bearings 12, 12 on a suitable support 13, the shaft 11 having an off-set portion 11a adjacent the mandrel for a purpose which will be described. The shaft 11 may have a knurled end 11b thereon in which a threaded bore 11c is provided to receive a threaded shaft 14 which is adjustably secured in a clamp at 15 which may be actuated by a knurl wheel 16 either to permit the shaft 14 to be slid through the clamp 15 or to secure the shaft 14 when desired. Associated with the mandrel 10 are filament supports 17 and 18, the support 17 having a shoulder 17a over which the filament extends and the support 18 having a hook 18a under which the filament extends to support a straight portion of the filament as indicated at 19 between the supports 17 and 18 in proper relation to be engaged by the mandrel 10 to wind the coil. The supports 17 and 18 may be arranged on a plate 20 secured in any suitable way on support 13. Grooved guides 21 and 22 are also provided for supporting and guiding the filament to the mandrel 10 and are arranged in such relation with respect to the supports 17 and 18 that the filament extends at angles to the straight portion 19 as indicated at 19a and 19b. The filament in the various views is generally indicated by 55

the letter F. The mandrel 10 has a filament engaging groove in the end thereof as indicated at 10^a, the ends of the mandrel at each side of the groove being curved as indicated at 10^b, 10^b so that when the filament wire is formed into a double helix the coils adjacent the outer end of the double helix will lie smoothly in true circle shape against the mandrel.

To wind a filament coil by the apparatus as described above, the clamp 15 is released and shaft 11 is slid forwardly in its bearings 12 to engage the groove 10^a of mandrel 10 with the straight portion 19 of the filament as shown in Figure 2. The shaft 14 is then clamped in clamp 15 so that it may not move and shaft 11 is turned as by engaging the knurled portion 11^b thereof which causes the shaft 11 to feed forwardly at a rate determined by the pitch of the screw threads on shaft 14 and in the bore 11^c. This pitch is, of course, the desired pitch of the double helical coil to be formed.

It will be noted that supports 17 and 18 are so arranged with respect to the end of the mandrel that as the filament is wound into the double helical coil as indicated in Figure 3, the windings of the respective coils of the double helix are spaced so as to lie comparatively close together in pairs with a comparatively large spacing between the pairs of coils which is determined by the pitch 30 of the screw on rod or shaft 14. The first half of the filament, as will be noted, passes under the hook 18^a and over the mandrel as shown in Figure 3, whereas the outer half of the filament passes over the shoulder 17^a and under the mandrel, the support 18 being arranged to guide the filament to the mandrel from a point farther inwardly of the outer end of the mandrel than the support 17. As stated above, with this type of winding, the filament when heat-treated in the 40 finished bulb expands in such a way under the action of the heat that the adjacent coils of the double helix move apart from the position shown in Figure 3 to the position shown in Figure 5^a. The stretches of the filament over the guides 21 and 22 may be connected with suitable means for maintaining the filament under tension so that it will assume the position thereof shown in Figure 2 preliminarily to winding and so that it will wind snug and true about the mandrel 10 during 50 the winding operation.

After the filament has been wound as shown in Figure 3, the leads and mount for the filament comprising leads L, L and bead B indicated in dash and dot lines are positioned as shown. Suitable yielding clamps 23, 23 arranged to cooperate with platforms 24, 24 and normally urged downwardly by springs such as spring 25 are provided to clamp the leads L, L as indicated in Figure 3 with the bead B positioned in the space provided 60 by the offset 11^a in the shaft 11 whereby the usual hook ends of the leads L, L may be engaged about the portions 19^a and 19^b of the filament F and clamped thereon by suitable means (not shown). By reason of the fact that the portions 19^a and 65 19^b extend at an angle, the filament is thus clamped to the leads so that it will be supported in proper position axially of the lamp bulb and cannot rock out of position, the angularity of the clamp filament preventing any tendency of the 70 clamped portions of the filament to rotate about their axes. It will be understood that the hooked ends of the leads are squeezed to compress the hooks about the angular stretches of the filament. After the filament is secured to the leads

L, the filament wire on each side of the leads is cut off and the filament and its mounting is secured in the lamp bulb as shown in Figure 5.

As will be apparent from Figure 4 looking at the end of the coil, the coil is perfectly round and when the incandescent lamp made as described herein is mounted so that the outer end of the coil provides the light source, this source will be perfectly round.

As stated in a preceding paragraph, the diameter of the coil must be sufficiently small that the resulting coil will be sufficiently stiff to prevent distortion by such jarring as ordinarily occurs in service. It has been found that with a mandrel .00875" in diameter, the usual filament 15 wire used in miniature lamps, when wound into a double helical coil is sufficiently stiff to resist distortion by jarring. A suitable coil is provided of this size using 128 threads to the inch on the rod 14, giving a finished coil .0273" in length, 20 having 3½ turns, and when tempered or set as described having a finished diameter of .0125". It is understood of course that these dimensions are merely demonstrative and may be varied.

After the filament has been mounted in the 25 lamp as shown in Figure 5, it is given a pre-treatment with heat by attaching the bulb in the usual socket and with a rheostat or other suitable electrically controlled device gradually increasing the current and voltage supplied to the lamp until 30 its operating current and voltage is reached. This causes the closely spaced adjacent coils of the double helix to move apart so that the coils of the filament in the finished lamp are substantially 35 equally spaced as indicated in Figure 5^a. Thereafter, whether the current is supplied gradually or suddenly to the lamp in service to its rated current and voltage, the coils do not move together and touch one another to cause shorting, a difficulty which has heretofore been experienced 40 in this type of coil. As a matter of fact, in the setting of the filament in its final form by the pre-heat treatment described, the coils may not move entirely to equally spaced positions such as shown in Figure 5^a, but in any event is subsequent 45 use any tendency for the coils to move under the action of heat will tend to separate them further rather than to bring them closer together. Regardless of whether they move to final equally spaced positions or not when heat treated, the 50 movement of the coils in any condition of service cannot be of an amount sufficient to cause touching and shorting.

Modifications of the invention may be resorted to without departing from the spirit thereof or 55 the scope of the appended claim.

What is claimed is:

The method of making a filament for incandescent lamps for use in diagnostic instruments and the like which comprises winding a single length 60 of wire into a helix and then winding reversely a return helix of the same size with the convolutions of each helix extending in parallel relation throughout the greater portion thereof and with a given convolution of one helix axially arranged closer to the adjacent similar convolution of the other helix than to the adjacent different convolution of the other helix, and subsequently moving the convolutions into a position where they are substantially equally spaced apart axial- 65 ly by heating the wire and gradually increasing the intensity of the heat.

WILLIAM J. HENRY.
